UNITED STATES PATENT OFFICE

2,003,568

FOLDER

Henry A. Wise Wood, New York, N. Y., assignor
to Wood Newspaper Machinery Corporation,
New York, N. Y., a corporation of Virginia

Original application April 28, 1927, Serial No.
187,375. Divided and this application July 15,
1931, Serial No. 550,887

2 Claims. (Cl. 270—18)

This is a division of my application for Patent Serial No. 187,375, filed April 28, 1927.

The invention is shown as applied to one unit of a printing press, it being understood that several units can be combined to form a more complete press, but this invention is not concerned with the way of combining them.

The principal objects of the invention are to provide improvements in the way of feeding the perfected web from the printing couples to the folder, including means for slitting the web and bringing the slit parts into a position, one over the other, and improved compensating rolls and adjustments therefor to be used for this purpose; to provide a set of adjustable turning bars and mountings therefor used in this part of the press; and to combine these features with an efficient form of drag roll, propeller, and slitting means for originally slitting the web before it passes to the drag roll.

The invention also involves the combination of these several features with each other in such a way as to provide a compact machine having the parts that have to be adjusted and attended to readily accessible so as to reduce the time lost in adjusting parts and render the press suitable for continuous use in newspaper printing plants.

Other objects and advantages of the invention will appear hereinafter.

Reference is to be had to the accompanying drawings in which

Fig. 1 is a diagrammatic view of the printing couples showing above them the means for slitting the web and guiding it to the drag roll in accordance with this invention;

Fig. 2 is a side view of the slitting mechanism illustrated at the left hand side of Fig. 1;

Fig. 3 is a plan of the guide roll showing the slitting knife in its cooperative relationship thereto;

Fig. 4 is a side view on enlarged scale of the means for adjusting one of the compensating rolls showing the telescoping arrangement by which the adjustment can be made at all times irrespective of the position of the roll;

Fig. 5 is a sectional view on the line 5—5 of Fig. 4 showing the compensating roll and its operating mechanism mostly in elevation;

Fig. 6 is an enlarged plan view of the means for holding the turning bars adjustably at each end;

Fig. 7 is an elevation of the same; and

Fig. 8 is a plan of the turning bars constituting a part of the mechanism shown in Fig. 1.

Referring first to Fig. 1, I have shown the press, or rather a press unit, comprising means for feed-

ing and perfecting the web and feeding the web through a set of compensating rolls after having first slit it, and then bringing the slit webs over the drag roll into the folder one over the other. It will be understood that these elements may constitute a complete press, but they can constitute an element of a multiple press for use in a newspaper printing plant, in which case one folder would serve to take the product from a plurality of press units.

It will be seen that I have shown the perfecting printing couples delivering the web upwardly over a guide roll 82 on a part of the frame secured to the main frame above the printing couple.

The web passes to a slitter roll 83 and acted upon by a slitter 84 which slits it preferably in two in the middle to form two webs. This slitter is shown in Figs. 2 and 3 in the form of a circular rotatable cutter mounted on an arm 85 which is fixed to a shaft 86 mounted on the frame. The frame is provided with a stationary rack 87 having two teeth. Fixedly mounted on the shaft 86 is an operating handle 88 having a spring-pressed latch 89 adapted to be secured in either of the notches in the rack 87 to hold the slitter in contact with the slitting rolls 83 as shown for operative purposes or to hold it back out of the way as may be desired.

The web being slit passes in two different paths, one directly to a compensating roll 90 and the other to a guide roll 91. The latter web passes back to a similar compensating roll 90 and the first named web passes back from its compensating roll 90 to another guide roll 91. This forms a loop in each web, the depth of which is regulated by the position of the compensating rolls. The latter web passes over a pair of turning bars 92. These turning bars, as will be understood, bring this web over laterally directly under the upper web so that they can be fed forward, one superposed over the other and practically registering with each other.

The compensating rolls 90 are alike. Each of them extends across the frame far enough to form a support for its own web or half web. The purpose is to adjust these rolls back and forth in the direction of the travel of the web to take up slack and secure the proper degree of tension. The adjustment in each case is provided for by a hand wheel 93 on a shaft 94 which shaft is provided with a worm 95 adapted to turn a corresponding worm wheel on a screw 96. This screw passes through a nut 97 pivotally mounted on the frame. Consequently the turning of the hand wheel 93 will adjust the screw longitudinally,

carrying with it a frame 98 on which the compensating roll 99 is journaled.

It will be understood that there is a frame 98 with associated parts on each side of the machine.

5 They slide freely on the frame as indicated in Fig. 5. The screw 96 is secured to a hollow square shaft 99 into which telescopes a solid square shaft 100 connected with a shaft 101 and adapted to be operated through a bevel gear connection by another hand wheel 102.

10 A corresponding shaft 101 is operated in the same way by another hand wheel 102 for controlling the other compensating roll. The hand wheels 102 are located in fixed positions where 15 they can be reached from the folder. It will be understood that each roll is adjusted by either hand wheel 93 or 102 and that these are provided at different points for the convenience of the operator. The hand wheel 93 in each case moves 20 along with the compensating roll and when moved far in is not perhaps so convenient for the operator. The hand wheels 102 are always in the same place, irrespective of adjustment. It is the movement of the compensating rolls bodily with their 25 frames 98 that necessitates the telescoping of the shafts 99 and 100, which are connected with each one of the shafts 101.

The turning bars 92 are set in the usual way but are supported by brackets 105, which are 30 mounted on longitudinal rods 106 constituting part of the frame. These brackets are provided with bolts 107 on which the end of each turning bar 92 is secured. Each bracket is provided with two projections 108 which are screw threaded to 35 receive screws 109 which are set into the turning bars to adjust them exactly 45° and hold them in that position.

40 It will be seen that the brackets 105 are double handed so that the same bracket can be used either way around or for a bar slanting in either direction. These brackets can be slid along the supporting rods 106 and the turning bars secured to them easily and readily attached and secured in either position as may be desired.

45 From the compensating roll or turning bars, as the case may be, the two webs are brought into contact, one over the other.

The web is delivered from the printing couples to the drag roll through a slitter and one of the 50 slit webs is moved over by turning bars into a position in vertical alignment with the other.

The turning bars are adjustably mounted by means which can be reversed to turn them in the opposite direction if desired. The webs passing from the slitter to the drag roll are kept taut by compensating rolls which can be adjusted either from their ends or from a stationary position on the frame.

5 These several features are combined with each other in such a way that the machine is compact and all parts are readily adjustable and 10 time is saved for performing these operations. This is an important feature on account of the necessity of speed in newspaper printing plants.

Although I have illustrated and described only one form of the invention, I am aware of the fact 15 that modifications can be made therein by any person skilled in the art without departing from the scope of the invention as expressed in the claims. Therefore I do not wish to be limited to all the details of construction herein shown 20 and described, but what I do claim is:—

1. In a printing press, the combination with a pair of web perfecting couples, of a roll over which the web therefrom is directed, a slitter adapted to slit the web in cooperation with said 25 roll, means for turning one of the half width webs into a position in vertical alignment with the other, compensating rolls, each located in a loop in one of said webs and adjustable transversely to its axis to register the web, means for 30 operating each of said compensating rolls from a point near the roll to move it along, and means in stationary position near the folder for moving each of the compensating rolls.

2. In a printing machine, the combination of 35 a slitter for dividing the web into two parts, a pair of compensating rolls arranged in a loop in each half of the web to keep the same taut, a frame on which said compensating rolls can be moved bodily for that purpose, carriages movable 40 along said frame, one carrying each of said compensating rolls, means on each carriage for moving it along, a shaft having a telescoping section connected with each carriage so that the shaft will be capable of being turned from a stationary 45 position irrespective of the position of the compensating roll, and means connected with each telescoping shaft for moving its carriage bodily along the frame.

HENRY A. WISE WOOD. 50
